CLAIM

The ornamental design for an ultrasound probe, as shown and described.

DESCRIPTION

FIG. 1 is a perspective view of an ultrasound probe showing my design,

FIG. 2 is a front view of the ultrasound probe,

FIG. 3 is a back view of the ultrasound probe,

FIG. 4 is a top view of the ultrasound probe,

FIG. 5 is a bottom view of the ultrasound probe,

FIG. 6 is a right side view of the ultrasound probe; and,

FIG. 7 is a left side view of the ultrasound probe.

The dashed lines in the drawings depict portions of the ultrasound probe that form no part of the claimed design. The dot-dash dot broken lines depict the boundaries of the claim and form no part thereof.

The article is an ultrasound probe used for an ultrasound diagnosis apparatus. A leading end part is abutted to a subject to transmit and receive an ultrasonic wave.
